(57) **CLAIM**

We claim the ornamental design for a cover member, as shown and described.

DESCRIPTION

FIG. 1 is a front perspective view of a cover member; FIG. 2 is a rear perspective view of the cover member; FIG. 3 is a rear elevational view of the cover member; FIG. 4 is a front elevational view of the cover member; FIG. 5 is a first side elevational view of the cover member, the opposite side elevational view being a mirror image thereof; FIG. 6 is a top plan view of the cover member; and, FIG. 7 is a bottom plan view of the cover member.

The dashed lines and broken lines are for purposes of illustrating environmental structure and form no part of the claimed design.

The cover member is broken away to indicate that no particular length is claimed.
